UNITED STATES PATENT OFFICE

102,508

DESIGN FOR JEWELLED METAL TRIMMING OR THE LIKE

Alfred F. Reilly, North Attleboro, Mass., assignor
to Evans Case Company, a corporation of Mas-
sachusetts

Application November 18, 1936, Serial No. 65,992

Term of patent 3½ years

To all whom it may concern:

Be it known that I, Alfred F. Reilly, a citizen
of the United States, residing at North Attleboro,
county of Bristol, and State of Massachusetts,
have invented a new, original, and ornamental
Design for Jeweled Metal Trimming or the like,
of which the following is a specification, refer-
ence being had to the accompanying drawing,
forming a part thereof.

In the accompanying drawing Figure 1 is a
plan view of a jeweled metal trimming showing
my new design. Fig. 2 is a side elevation thereof.

I claim:

The ornamental design for a jeweled metal
trimming or the like as shown.

ALFRED F. REILLY.
